UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

TEMPORARY BINDER OR LOOSE-SHEET HOLDER.

1,150,472.

Specification of Letters Patent. Patented Aug. 17, 1915.

Application filed August 27, 1914. Serial No. 858,971.

To all whom it may concern.

Be it known that I, GEORGE P. WIGGINTON, citizen of the United States, residing at Kalamazoo, county of Kalamazoo, State 5 of Michigan, have invented certain new and useful Improvements in Temporary Binders or Loose-Sheet Holders, of which the following is a specification.

This invention relates to improvements in 10 temporary binders or loose sheet holders.

My present improvements relate particularly to the adjusting mechanism.

I have especially designed my improvements for embodiment in temporary binders or loose sheet holders of the type shown 15 in U. S. Letters Patent to Bushong, Serial No. 851,276, issued April 23, 1907. My improvements may, however, be readily adapted to binders considerably modified in general structure.

The main objects of this invention are, first, to provide in a temporary binder or loose sheet holder an improved adjusting mechanism by means of which the binder 25 may be quickly adjusted to permit the insertion or removal of sheets or leaves or to secure the sheets within the binder; second, to provide an improved temporary binder or loose sheet holder in which the binding 30 strips may be released so that they may be quickly extended to their full length and also quickly retracted; third, to provide an improved temporary binder or loose sheet holder having these advantages which is 35 simple and convenient in operation.

Further objects, and objects relating to structural details, will definitely appear from the detailed description to follow.

I accomplish the objects of my invention 40 by the devices and means described in the following specification.

The invention is clearly defined and pointed out in the claims.

A structure which is a preferred embodiment 45 of my invention is clearly illustrated in the accompanying drawing forming a part of this specification, in which:

Figure I is a detail view of a structure embodying the features of my invention

with the covers extended, the outer walls 50 of the covers being removed. Fig. II is a detail longitudinal section on a line corresponding to line 2—2 of Fig. I, with the covers closed, the covers and clamping members being shown spaced apart. Fig. III is 55 an enlarged detail longitudinal section on a line corresponding to line 3—3 of Fig. I, showing details of the adjusting mechanism. Fig. IV is an enlarged detail section on a line corresponding to line 4—4 of Fig. I, 60 showing further details of the adjusting mechanism. Fig. V is a detail longitudinal section taken on a line corresponding to line 5—5 of Fig. I.

In the drawing similar reference characters refer to similar parts throughout the several views, and the sectional views are taken looking in the direction of the little arrows at the ends of the section lines.

Referring to the drawing, the covers are 70 designated generally by the numerals 1 and 2. The covers preferably consist of rectangular frames 3 having inner walls 4 and outer walls 5 secured thereto to provide chambers within the covers.

The structure illustrated is provided with 75 clamping bars or guide members 6 pivotally mounted on the hinge members 7 projecting on the inner ends of the covers. These binding members are illustrated and described in the Bushong patent referred to.

The binding strips 8 are secured to the cover 2 at 9 and telescope into the cover 1. The binding strips are provided with a cross piece 10 having a finger piece 11 disposed 85 through the longitudinal slot 12 in the inner wall of the cover 1. This finger piece is adapted to be folded or collapsed and is shown in its folded position in the drawing. As its details form no part of my present invention, I do not illustrate the same herein.

The binding strips are releasably secured to means for tightening or applying stress thereto and when disengaged or released from this adjusting means the covers may 95 be pulled apart freely or the binding strips retracted into the cover 1 by means of the finger piece 11. This adjusting means con-

- bracing said rack, an actuating shaft disposed through the arms of said slide, a pinion on said actuating shaft disposed between the arms of said slide to coact with said
- 5 rack, U-shaped binding strip securing members mounted on said actuating shaft, said shaft being disposed through the arms of said securing members, said binding strips being arranged between the arms thereof,
- 10 a clamping shaft arranged through the arms of said actuating shaft slide and said securing members and provided with eccentric clamping portions between the arms of said securing members.
- 15 4. In a temporary binder, the combination with the covers, of binding strips extending between the covers, a rack on one of said covers, an actuating shaft slide embracing said rack, an actuating shaft mounted on
- 20 said slide and provided with a pinion coacting with said rack, binding strip securing members mounted on said actuating shaft, a clamping shaft mounted on said slide and said securing members, a toothed stop wheel
- 25 on said actuating shaft, a coacting stop on one of said securing members, said actuating shaft being longitudinally movable for engagement and disengagement of said stops, a stop on said actuating shaft coacting with
- 30 one of said securing members to limit the longitudinal movement of said shaft, a spring arranged on said actuating shaft to normally cause the engagement of said stops, one end of said spring being supported by
- 35 said slide and the other engaging a collar on said actuating shaft.
5. In a temporary binder, the combination with the covers, of binding strips extending between the covers, a rack on one of said
- 40 covers, an actuating shaft slide, an actuating shaft mounted on said slide and provided with a pinion coacting with said rack, binding strip securing members mounted on said actuating shaft, a clamping shaft
- 45 mounted on said slide and said securing members, a toothed stop wheel on said actuating shaft, a coacting stop on one of said securing members, said actuating shaft being longitudinally movable for engagement
- 50 and disengagement of said stops, a spring arranged on said actuating shaft to normally cause the engagement of said stops.
6. In a temporary binder, the combination with the covers, of binding strips extending
- 55 between the covers, a rack on one of said covers, an actuating shaft slide embracing said rack, an actuating shaft mounted on said slide and provided with a pinion coacting with said rack, binding strip securing
- 60 members mounted on said actuating shaft, a clamping shaft mounted on said slide and said securing members, a toothed stop wheel on said actuating shaft, and a coacting stop movable with said actuating shaft slide.
7. In a temporary binder, the combination 65 with the covers, of binding strips extending between the covers, binding strip securing members mounted on one of said covers, a clamping shaft mounted on said securing members, an actuating shaft mounted on 70 said securing members, a rack mounted on said cover, a pinion on said actuating shaft coacting with said rack, a toothed stop wheel on said pinion shaft, a coacting stop on one of said securing members, said shaft being 75 longitudinally movable for the engagement and disengagement of said stops, and a spring arranged on said shaft to normally cause the engagement of said stops, said clamping shaft and pinion shaft being adapted to be operated from the outside of the cover by means of a key.
8. In a temporary binder, the combination 80 with the covers, of a binding strip extending between the covers, a binding strip adjusting member slidably mounted on one of said covers, means for releasably securing said binding strip to said adjusting member carried thereby, an actuating pinion on said adjusting member, a rack mounted on said cover to coact with said pinion, said pinion being adapted to be operated from the outside of the cover by means of a key, said binding strip being freely adjustable relative to said adjusting member when released 85 from therefrom, and means for adjusting said binding strip when it is released from said adjusting member.
9. In a temporary binder, the combination 90 with the covers, of a binding strip extending 100 between the covers, an adjusting member slidably mounted on one of said covers, a rod for securing said binding strip to said adjusting member movable therewith, an actuating shaft mounted on said adjusting 105 member, a pinion on said actuating shaft, and a rack mounted on said cover to coact with said pinion, both said shaft and rod being adapted to be operated from the outside of the cover by means of a key, said 110 binding strip being freely adjustable relative to said adjusting member when released therefrom.
10. In a temporary binder, the combination 115 with the covers, of a binding strip extending between the covers, an adjusting member mounted on one of said covers, a rod for securing said binding strip to said adjusting member movable therewith, an actuating shaft mounted on said adjusting member, a pinion on said actuating shaft, and a rack mounted on said cover to coact with said pinion, said binding strip being 120 freely adjustable relative to said adjusting member when released therefrom.
11. In a temporary binder, the combination 125 with the covers, of binding strips extending between the covers, clamping mem-

bers slidably mounted on one of said covers, a clamping shaft mounted on said clamping members, a pinion shaft mounted on said members, a rack mounted on said cover, and 5 a pinion on said pinion shaft coacting with said rack.

12. In a temporary binder, the combination with the covers, of binding strips extending between the covers, a securing rod 10 disposed transversely of one of the covers, members movable with said rod, an actuat-

ing shaft carried by said members, a pinion on said actuating shaft, and a rack mounted on said cover coacting with said pinion.

In witness whereof, I have hereunto set 15 my hand and seal in the presence of two witnesses.

GEORGE P. WIGGINTON. [L.S.]
